By *Charles L.*
Attorney

UNITED STATES PATENT OFFICE.

ABRAHAM JOHNSON, OF OPPORTUNITY, WASHINGTON.

COW-TAIL HOLDER.

Application filed March 7, 1923. Serial No. 623,468.

To all whom it may concern:

Be it known that I, ABRAHAM JOHNSON, a citizen of the United States, residing at Opportunity, in the county of Spokane and State of Washington, have invented a new and useful Cow-Tail Holder, of which the following is a specification.

This invention relates to cow tail holders, and the object thereof is to provide a simple 10 cheaply constructed device of this character which may be quickly applied and removed and will effectively prevent the switching of a cow's tail.

With the foregoing and other objects in view which will appear as the description proceeds, the invention resides in the combination and arrangement of parts and in the details of construction hereinafter described and claimed, it being understood 20 that changes in the precise embodiment of the invention herein disclosed may be made within the scope of what is claimed without departing from the spirit of the invention.

In the accompanying drawings:—

25 Figure 1 represents a side elevation of this improved holder shown applied.

Fig. 2 is a top plan or edge view thereof, and

30 Fig. 3 is an enlarged side elevation of one end of the holder.

In the embodiment illustrated, a leg encircling strap 1 is shown which may be of any suitable material and has secured to one end thereof a hook 2, the bill 3 of which lies in close proximity to the body of the hook to prevent its accidental disengagement.

A cooperating fastening member 4 is mounted at the other end of the strap 1 and 40 as shown comprises a wire loop substantially rectangular in form with one cross bar of which the strap 1 is engaged and secured by stitching or otherwise. The opposed cross bar 5 has an inwardly extending laterally 45 deflected loop 6 with which the hook 2 is designed to be detachably engaged as is shown clearly in Fig. 2.

The member 4 is constructed of heavy wire one end of which has an eye 7, which wire 50 after the formation of the cross bar 5 is extended to provide a substantially U-shaped loop 8 with an eye 9 formed at its free end which is hooked around the end of the cross bar 5 at a point opposite to that which is en-

gaged by the eye 7. The cross bar 8^a of the 55 loop 8 has pivotally mounted thereon a tail clamping member 10. This member 10 is composed of two outwardly bowed jaws 11 and 12, the free ends 13 and 14 of which are arranged inlapping relation when the jaws 60 are closed and the inner jaw 14 has a series of teeth 15 which are designed to engage the hairs of the cow's tail when the device is applied and prevent slipping of the member 10 on the cow's tail. The inner ends of the 65 jaws 11 and 12 have diverging ends 16 and 17 with apertured lugs 18 at their inner ends which are arranged inlapping relation and through which the cross bar 8^a of the loop 8 is passed. A coiled spring 19 is mounted on 70 the cross bar 8^a between the lugs of clamp 10 and the ends of said spring are engaged one with the inner face of the end 16 and the other with end 17 as is shown at 20 whereby the spring exerts its tension to force these 75 ends apart, and force the jaws 11 and 12 toward each other into clamping position.

From the above description it will be obvious that this holder may be quickly applied by simply passing the strap 1 around 80 the cow's hind leg and engaging the hook 2 with the loop 6 of the member 4. The clamp 10 is then snapped around the cow's tail and all possibility of switching of the tail will thus be prevented.

85 Various changes in the form, shape, proportion and other minor details of construction may be made without departing from the spirit and principle or sacrificing of the advantages of the claimed invention.

I claim:—

In a cow tail holder a leg encircling strap, a tail clamp, a connector between said clamp and strap comprising a single piece of wire bent to form two loops arranged in longitudinal alignment and one loop having a cross bar equipped with a laterally deflected loop, the tail clamp being pivotally mounted on the cross bar of the other loop, and a hook carried by said strap for detachable engagement with said deflected loop.

95 In testimony that I claim the foregoing as my own, I have hereto affixed my signature in the presence of two witnesses.

ABRAHAM JOHNSON.
